No. 841,775.

PATENTED JAN. 22, 1907.

J. P. GARBER.
SCHOOL DESK.
APPLICATION FILED OCT. 14, 1905.

UNITED STATES PATENT OFFICE.

JOHN PALMER GARBER, OF RIDLEY PARK, PENNSYLVANIA.

SCHOOL-DESK.

No. 841,775.

Specification of Letters Patent.

Patented Jan. 22, 1907.

Application filed October 14, 1905. Serial No. 282,864.

To all whom it may concern:

Be it known that I, JOHN PALMER GARBER, a citizen of the United States, residing at No. 9 Darby street, Ridley Park, in the county of Delaware and State of Pennsylvania, have invented certain new and useful Improvements in School-Desks, of which the following is a specification.

This invention relates to an adjustable school-desk, and has for its object to provide means whereby the top, and particularly that portion adjacent to the pupil on which the arms of the pupil rest, may be readily adjusted vertically to not only assume several positions most convenient for requirements of different classes of work, but to adjust for pupils of different sizes.

Heretofore in the branch of the art to which this invention pertains school-desks have been provided with adjustable tops and seats, there being numerous methods of effecting these adjustments vertically. The tops have also been hinged and locks have been provided to hold the top in several adjusted positions. There are several objections, however, to these constructions, the chief of which is that to adjust the desks it is necessary to employ the services of the janitor, whereas the top and seats should be easily adjusted by the pupil, especially since it is often desirable to change the height and the angle of the top of the desk several times during a session of the school.

The invention consists in the parts and combination of parts shown in the drawings, described in the specification, and more particularly pointed out in the claims.

In the drawings, Figure 1 is a perspective view of a school-desk embodying the features of my invention. Fig. 2 is a vertical sectional view of the upper portion of the same, the top being shown in a horizontal position in full lines and in a lowered position in dotted lines. Fig. 3 is a detailed view of one of the sides of the top, this view illustrating the means for pivoting the latch, and the side flange for incasing the same. Fig. 4 is a detailed view of the latch. Fig. 5 is an enlarged sectional detail view illustrating more particularly the latch-lever and spring.

In carrying out my invention I employ side standards 1, a seat 2, pivotally secured thereto at 3, a back 4, and a book-shelf 5, the standards being horizontal for a short distance, as shown at 6, upon which is secured a fixed portion 7 of the top, the for-

ward portion thereof extending beyond the horizontal portion 6 of the side standards, as shown in Fig. 2, forming a pocket between the top and the side standards, the standards 60 being inclined, as at 8, the front vertical portion thereof being serrated, as at 9.

10 designates the adjustable top, to each side of which are secured plates 11, provided with ears 12, by which the plates may be secured to the top. The plates 11 are provided with a hole 13, through which and through the side standards 1 passes a rod 14, having nuts 15 upon its outer ends by which means the plates, and consequently the top, are pivotally 70 secured to the side standards, the top having a movement from a position substantially horizontal (shown in full lines in Fig. 2) to an incline position, limited by the inclination of the portion 8 of the side standards, which act 75 as a stop for the top in its lowered position and, if desired, can be faced with felt, rubber, or other material to deaden the noise when the top comes in contact therewith. Plate 11 is provided with a side flange 16, slotted at 80 17, into which rests a horizontal portion 18 of the catch. The catch is preferably formed of a rod bent upon itself at the center, the bent portion being flattened to form a lever 19, the ends of the rod being bent downward, 85 as at 20, to form catches housed by the plate 11 and the side flanges 16, (shown in Fig. 2,) the catches moving in alinement with the serrations 9 on the front of the side standards 1 and engage therewith to adjust the top at 90 any desired height or inclination. The under side of the top is provided with a spring 21, which normally presses the lever 19 downward and the catches into engagement with the serrations 9. To adjust the top, it is only 95 necessary to press the lever 19 to disengage the catches, when the top may be raised or lowered, and by releasing the lever the catches automatically engage in the serrations. The holes 13 in the side plates 11 are located substantially in vertical alinement with the rear side of top 10, and the front edge of the rigid portion 7 of the top extends in front of the rod 14, whereby the rear edge of the top 10 is at all times beneath the rigid portion 7 of the 105 top no matter in what inclination the top may be adjusted. Consequently the upper surface of the desk is unbroken and presents a good appearance.

What I claim is—

1. In a school-desk, side standards having a horizontal upper portion and an inclined

110

- portion extending forward, therefrom, a top formed of two portions, a rigid horizontal portion secured to the horizontal upper face of the side standards and extending forward 5 beyond its point of attachment, a movable portion of top pivoted to the side standards and adapted to swing in the arc of a circle from a horizontal position to an inclined position limited by the inclination of the forward portion of the side standards, the forward edge of the movable portion of top moving at all times beneath the free end of the rigid portion of top, and means for securing the movable portion of top in an adjusted position.
- 15 2. In a school-desk, side standards having serrated rear edges, a top pivotally secured to the standards at a point below the upper surface of the top and substantially in alignment 20 with the rear edge of the top, side plates carried by the top, a rod pivotally secured in the

side plates near the front edge having a catch at each end in alignment with the serrations in the standards, and a lever carried by the rod for actuating the catches.

25

3. In a school-desk, side standards, a top formed of two portions, a rigid horizontal portion and a movable portion, side plates secured to the movable portion having side flanges, a rod pivotally secured in the side flanges having a catch at each end housed between the body of the plate and the side flanges, a lever for rocking the rod and moving the catches, and serrations upon the standards with which the catches normally 30 engage.

30

In testimony whereof I affix my signature in presence of two witnesses.

JOHN PALMER GARBER.
